UNITED STATES PATENT OFFICE.

GEORGE H. GILMAN, OF BOSTON, MASSACHUSETTS, ASSIGNOR TO SULLIVAN MACHINERY COMPANY, A CORPORATION OF MASSACHUSETTS.

FLUID MOTOR.

Application filed March 25, 1916, Serial No. 86,815. Renewed May 20, 1921. Serial No. 471,157.

To all whom it may concern:

Be it known that I, GEORGE H. GILMAN, a citizen of the United States, residing at Boston, in the county of Suffolk and State of Massachusetts, have invented certain new and useful Improvements in Fluid Motors, of which the following is a full, clear, and exact specification.

My invention relates to fluid motors, and 10 more particularly to valveless motors of the type having a reciprocating percussive piston adapted to impart rapidly recurring blows to a drill steel, although my invention is not limited to use in that connection.

15 It has for its object to provide an improved motor wherein a single charge of a pressure fluid, such as air, acts to reciprocate the piston to and fro in its movement in the cylinder, the forward movement of the piston 20 ton being much more rapid than the return stroke thereof. More specifically, my invention has among its objects to increase the power of the piston blow and at the same time balance the piston in an improved manner and reduce the cost of manufacture of 25 the device. These and other objects of my improvement will hereinafter appear.

In the accompanying drawings, I have for 30 purposes of illustration shown one embodiment which my invention may assume in practice.

In these drawings,—

35 Figure 1 is a partial longitudinal developed section of a motor equipped with this form of my improvement, the section being taken on line 1—1 of Figure 3 as to the rear end of the cylinder, and on a line disposed at a slight angle to the line 1—1 as to the front end of the cylinder, and the piston being 40 shown in its extreme rearward position.

Figure 2 is a view similar to Figure 1, the section being similarly taken, and the piston being shown in its extreme forward position.

45 Figure 3 is a transverse sectional view taken on line 3—3 of Figure 1.

Figure 4 is a transverse sectional view taken on line 4—4 of Figure 1.

Figure 5 is a transverse sectional view taken on line 5—5 of Figure 1.

50 Figure 6 is a transverse sectional view taken on line 6—6 of Figure 1.

In these drawings, I have illustrated a cylinder 1 having a piston chamber 2 therein in which moves a piston member comprising 55 two heads 3 and 4 of the same external diam-

eter, these heads being connected by a reduced portion 5, and the front head 4 being adapted to actuate a tool or steel 6 carried in any suitable housing 7, preferably through an intermediate tappet or anvil 8 of suitable 60 construction seated in the front head 9 of the cylinder.

In my improved construction air is admitted to the piston from a suitable inlet 10 by a controlling valve 11 of any desired 65 form, which delivers the air through a passage 12 to a receiving chamber 13 formed in the rear head 14 of the cylinder. This chamber, as shown, is provided with a plurality of oppositely disposed radially extending 70 outlets 15 communicating with a plurality of series of parallel passages 16, three being shown herein in each series, extending longitudinally of the cylinder to a point substantially midway of the ends of the latter 75 where these groups of passages communicate with the interior of the cylinder through oppositely disposed ports 17, the latter preferably being so located as to be opposite the reduced portion 5 of the piston when the 80 latter is in its retracted position shown in Figure 1.

This reduced portion thus forms an annular chamber 18 which receives the charge of air admitted from the supply passages 10, 85 and serves both as a conducting and transporting means for fluid pressure as will be hereafter evident. For the purpose of conducting the pressure fluid from this chamber to the rear end of the cylinder I have arranged 90 a plurality of ports 20 communicating with a plurality of series of parallel passages 21 formed in the cylinder, preferably of the same number and arrangement as the passages 16, and disposed between those passages, but leading rearward and communicating through ports 22 with oppositely disposed transverse passages 23 formed in the rear cylinder head, so that the air may pass inward into a rear pressure chamber 24 100 formed in the rear piston head 3, and through its pressure against the rear end of the piston herein including the pressure surface 25 of the chamber, force the piston forward with great rapidity.

105 As the piston moves forward, i. e. toward the right in Figure 1, its rear head 3 will first close the ports 20 and thereby cut off the supply of air from the chamber 18 to the passages 21. As the piston moves still 110

2
 further forward, the same head thereon will also close the ports 17 and cut off the air from the passages 16 to the chamber 18. As a result, the air which remains in the chamber 18 after the ports 20 are closed supplemented, i. e. with its pressure somewhat raised by that which has entered the same through the ports 17 in the brief interval before those ports are also closed, is trapped within the chamber 18 and carried bodily forward with the piston, while the air which has acted upon the rear end of the piston is permitted to exhaust, oppositely disposed exhaust openings 26 therefor being cleared by the head 3 as the latter moves forward and preferably shortly after that head has closed the ports 17. As the piston thus moves forward with the air trapped in the chamber 18, and shortly after the ports 17 are closed, the chamber 18 surrounding its reduced portion 5 is brought into communication with a plurality of peripherally disposed, radial ports 27, herein three, each communicating with a series of longitudinally extending parallel passages 28. These passages 28 in turn communicate through peripherally disposed ports 29 with the front end of the cylinder, and are obviously put in communication with the supply of air in the chamber 18 shortly before the front piston head 4 has struck the tappet 8, so that the air admitted through these passages 28 and ports 29 to the front end of the cylinder may act expansively on the front pressure surface 30 of the piston head 4 and thereby drive the latter backward to its initial position, a plurality of exhaust ports 31 being provided in the front end of the cylinder to permit the exhaust of this air after it has expanded sufficiently to insure the return of the piston to its initial position shown in Figure 1.

Briefly reviewing the operation of the motor herein used as an illustration of my invention, the air entering through the ports 17 passes through the passages 21 and ports 23 to the rear end of the piston, thereby causing the latter to move to the right as shown in Figure 1, and to trap a charge of air in the annular chamber 18. This charge of air is then carried bodily along with the piston until the chamber 18 is put in communication with the passages 28, whereupon it is permitted to pass to the front end of the piston and act expansively upon the front pressure surface 30 thereof to return the piston from the position shown in Figure 2 to the position shown in Figure 1, the air which has previously acted upon the rear pressure surface of the piston being first exhausted through the port 26, and the air which has acted expansively on the pressure surface 30 being later exhausted through the port 31. Attention is here also directed to the fact that the new charge

begins to be admitted to the chamber 18 surrounding the reduced portion 5 of the piston shortly after the ports 27 are closed, but this chamber does not communicate with the rear end of the cylinder until the ports 20 are opened so that a new charge of air at pipe line pressure is put in communication with the rear pressure surfaces of the piston as soon as the ports 20 are cleared by the piston, thus enabling this air to cushion the return stroke of the piston without unduly retarding its rearward travel or causing an undue shortening of the stroke.

It will be noted that in my improved construction, the piston heads are of the same external diameter so that the cylinder may be provided with a bore of uniform diameter, and the cost of manufacturing the same and the pistons be thus minimized. Attention is also directed to the fact that through the provision of my improved construction wherein the air is supplied through a plurality of series of ports disposed radially about the piston, the air acts in such a manner on the piston as to balance the latter, and thereby insure even piston movement and a long piston life. These and other advantages of my improved construction will, however, be apparent to those skilled in the art.

95
 While I have in this application specifically described one embodiment which my invention may assume in practice, it is to be understood that, as indicated above, this embodiment of the same is used for purposes of illustration, and that the invention may be modified and embodied in other forms without departing from its spirit, it being my intention to include all such modifications within the scope of the appended 100 claims.

105
 105 What I claim as new and desire to secure by Letters Patent is:

110
 110 1. In a fluid motor, a cylinder, a piston therein having a chamber, said piston being movable to trap a charge of fluid wholly within the confines of said chamber, and cooperating means for delivering said fluid to one end of said cylinder.

115
 115 2. In a fluid motor, a cylinder, a piston therein having a chamber, said piston being movable to trap and convey a charge of fluid at inlet pressure within the confines of said chamber, and cooperating means for reciprocating said piston in opposite directions 120 communicating with the opposite ends of said cylinder and successively communicating with said chamber, a portion of said means being adapted to deliver the trapped charge to one end of the cylinder.

125
 125 3. In a fluid motor, a cylinder, a piston therein having an intermediate reduced portion whereby a chamber is formed on said piston, said piston being movable to trap a charge of fluid within the confines of said 130

- chamber and convey the same at constant pressure on movement of the piston, and co-operating means for reciprocating said piston in opposite directions communicating 5 with the opposite ends of said cylinder and successively communicating with said chamber, a portion of said means being adapted to deliver the trapped charge to one end of the cylinder.
- 10 4. A percussive fluid motor comprising a cylinder of uniform diameter, a piston movable therein having heads of equal diameter and an intermediate reduced portion, and means including a single set of inlet ports 15 opened and closed by said piston for supplying fluid to said reduced portion and therefrom successively to the opposite ends of said cylinder.
5. A percussive fluid motor comprising a cylinder of uniform diameter, a piston having a plurality of heads of equal diameter and an intermediate reduced portion, one of said heads having a pressure chamber therein, and means including ports opening into 20 said cylinder substantially centrally thereof and opened and closed by said piston for supplying fluid to said reduced portion and therefrom to the opposite ends of said cylinder.
- 25 6. In a percussive fluid motor, a cylinder of uniform diameter, and a piston movable therein having heads of equal diameter and an intermediate reduced portion, said cylinder having a plurality of parallel supply 30 passages extending from one end thereof and disposed around the same, each passage communicating with said reduced portion through a single port, and a plurality of passages communicable with said reduced 35 portion, when the reduced portion of the piston is out of communication with said supply ports, and leading to the other end of said cylinder.
- 40 7. In a percussive fluid motor, a cylinder of uniform internal diameter, and a piston having heads on its opposite ends and an intermediate reduced portion, said cylinder having a plurality of series of supply 45 passages extending from one end thereof and located in the wall thereof, each passage communicating with said reduced portion through a single port and a plurality of series of passages communicable with said reduced portion and leading to the other 50 end of said cylinder, said first named and last named passages being separated by a distance greater than the length of the reduced portion of the piston.
- 55 8. In a percussive fluid motor, a cylinder, and a piston having heads at its opposite ends and an intermediate reduced portion, said cylinder having an inlet port adjacent its middle and ports leading to the ends of 60 the cylinder and communicating with the bore thereof on opposite sides of said inlet port, and said reduced portion of said piston being adapted to connect said inlet port and one of said passages in one position of the piston and being communicable with the other of said passages in another position of 65 the piston when said inlet port is closed.
9. In a percussive fluid motor, a cylinder and a piston movable therein having a plurality of heads and an intermediate chambered portion, said cylinder having an inlet 70 port communicating with said intermediate portion, an outlet port communicating therewith and with one end of said cylinder, said outlet port being spaced longitudinally from said inlet port, and a second outlet port communicating with the opposite end of said cylinder and spaced longitudinally from said inlet port a greater distance than said first named outlet port, said ports being successively controlled by said piston during a 75 movement thereof in one direction.
10. In a percussive fluid motor, a cylinder, and a piston movable therein having a plurality of heads and an intermediate reduced portion, said cylinder having a plurality 80 of inlet ports communicating with said reduced portion, a plurality of outlet passages leading from said reduced portion to one end of said cylinder, and a plurality 85 of outlet passages leading to the opposite end of said cylinder, said first named outlet passages being closed by the piston prior to said inlet ports, and said last named outlet passages being subsequently opened thereby.
11. In a percussive fluid motor, a cylinder, and a piston movable therein having a plurality of heads and an intermediate chamber, said cylinder having an inlet port communicating with said intermediate chamber, 90 an outlet port communicating with one end of said cylinder, and a second outlet port communicating with the opposite end of said cylinder, said ports being so disposed 95 that the inlet port is closed by said piston after the closure of said first named outlet port and before the opening of said second outlet port thereby.
12. In a percussive fluid motor, a cylinder, and a piston movable therein having a plurality of heads of equal diameter and an intermediate portion, said cylinder having passages therein communicating with said intermediate portion in different positions of said piston and with the opposite ends 105 of said cylinder, and an inlet opened and closed by said piston, communicating with said intermediate portion prior to the completion of the backward stroke of said piston, said inlet and intermediate portion being adapted to effect the transmission of 110 operating fluid to both of said operating passages.
13. In a percussive fluid motor, a cylinder, and a piston movable therein having a 115

plurality of heads and an intermediate portion, said cylinder having passages therein communicating with said intermediate portion in different positions of said piston and 5 with the opposite ends of said cylinder and an inlet communicating with said intermediate portion prior to the completion of the backward stroke of said piston and after the closure of one of said sets of passages 10 and before the opening of the other.

14. In a percussive fluid motor, a cylinder having a chambered rear head, a piston movable in said cylinder having heads of equal diameter and an intermediate reduced 15 portion, means including an inlet for supplying fluid from said chambered head to said reduced portion, said means being alternately opened and closed by said piston, and means communicable with said reduced 20 portion and controlled by said piston for delivering pressure fluid from said inlet to opposite ends of said cylinder in different positions of said piston.

15. A double acting valveless percussive 25 fluid motor comprising a cylinder of constant diameter and a piston having heads of equal diameters, said motor including pressure fluid controlling means providing a single charge of pressure fluid for each cycle 30 of reciprocation of said piston in said cylinder.

16. A valveless percussive fluid motor comprising, in combination, a cylinder of constant diameter, a piston therein having 35 heads of equal diameters and an intermediate chamber, initial pressure fluid admission means delivering a predetermined volume of pressure fluid to said intermediate chamber, and conduit means effective after 40 closure of said admission means to admit said pressure fluid from said intermediate chamber to one end of said cylinder to reverse the direction of reciprocation of said piston.

17. A valveless pressure fluid motor comprising a cylinder of constant diameter and a piston therefor, said cylinder and piston presenting end piston chambers and an intermediate chamber, said motor including 50 pressure fluid distributing means providing for the transfer in one direction of a predetermined charge of pressure fluid in said intermediate chamber to actuate said piston in the opposite direction.

18. A pressure fluid motor comprising a cylinder of constant diameter and a piston therefor, said cylinder and piston presenting end piston chambers and an intermediate chamber, said motor including pressure 60 fluid supply means controlled by said piston for admitting pressure fluid to said intermediate chamber, conduit means for conducting pressure fluid from said intermediate chamber to one of said end piston chambers to actuate said piston in one direction,

and means effective after closure of said conduit means to admit pressure fluid to the other of said end piston chambers.

19. A double acting valveless percussive fluid motor comprising a cylinder of constant diameter and a piston having heads of equal diameters, said motor including pressure fluid controlling means providing a single charge of pressure fluid for actuating said piston through each cycle of reciprocation of the piston in said cylinder.

20. A valveless percussive fluid motor comprising, in combination, a cylinder of constant diameter, a piston therein having heads of equal diameter, a lateral fluid inlet controlled by said piston, and cooperating pressure fluid delivering means for alternately distributing in opposite directions to the opposite ends of said cylinder a single charge of pressure fluid during each cycle of reciprocation of said piston in said cylinder.

21. A valveless percussive fluid motor comprising, in combination, a cylinder of constant diameter, a piston therein having heads of equal diameter, a lateral fluid inlet controlled by said piston, and piston controlled pressure fluid distributing means for alternately distributing in opposite directions to the opposite ends of said cylinder a single charge of pressure fluid during each cycle of reciprocation of said piston in said cylinder.

22. A valveless percussive fluid motor comprising, in combination, a cylinder of constant diameter, a piston therein having heads of equal diameter and an intermediate chamber, a lateral inlet for admitting fluid to said intermediate chamber, said inlet being opened and closed by said piston, and pressure fluid delivering means for alternately distributing in opposite directions to the opposite ends of said cylinder a single charge of fluid during each cycle of reciprocation of said piston in said cylinder.

23. A valveless percussive fluid motor comprising, in combination, a cylinder of constant diameter, a piston therein having heads of equal diameters and an intermediate reduced portion, a lateral fluid inlet opened and closed by one of said heads, and pressure fluid delivering means for alternately distributing in opposite directions to the opposite ends of said cylinder a single charge of pressure fluid during each cycle of reciprocation of said piston in said cylinder.

24. A valveless fluid pressure motor having a ported cylinder provided with an inlet, and a chambered piston cooperating therewith to conduct the fluid pressure supply for one end of said cylinder, and transport the fluid pressure supply for the other end.

25. In a valveless fluid pressure motor,

a cylinder, a piston reciprocable therein, and means for effecting reciprocation of said piston in said cylinder including a chamber of constant volume to which fluid 5 is supplied in one position of said piston and from which said fluid is delivered to one end of said cylinder in another position of said piston.

26. In a valveless fluid pressure motor, 10 in combination, a ported cylinder provided with an inlet port, a piston reciprocable in said cylinder and means for supplying fluid

pressure to the opposite ends of said cylinder including a passage communicating with said cylinder at one end thereof and 15 also at a point spaced from said end, and a chamber carried by said piston and operative to receive and convey fluid at full inlet pressure, said chamber being communicable with said inlet port and said passage only 20 at different times.

In testimony whereof I affix my signature.

GEORGE H. GILMAN.
